UNITED STATES PATENT OFFICE.

JOHN S. WHITNEY, OF LOWELL, MASSACHUSETTS.

LUBRICATING APPARATUS FOR BEARINGS IN MACHINERY.

SPECIFICATION forming part of Letters Patent No. 244,013, dated July 5, 1881.

Application filed April 6, 1881. (No model.)

To all whom it may concern:

Be it known that I, JOHN S. WHITNEY, of Lowell, in the county of Middlesex and State of Massachusetts, have invented a new Improvement in Lubricating Apparatus for Heavy Journal-Bearings in Fast-Running Machinery, of which the following is a specification.

The object of this invention is to provide an automatic oiler for heavy fast-running bearings, whereby all waste of oil and the entrance of dust and dirt upon the bearings are prevented.

Figure 1 is a front elevation of the device in position on a journal-bearing. Fig. 2 is a partly-sectional plan of the same on line *x x*, Fig. 1. Fig. 3 is an enlarged sectional elevation on line *y y*, Fig. 1. Fig. 4 is a cross-section on line *z z*, Fig. 3. Fig. 5 is an enlarged sectional elevation of the supporting and guiding mechanism of the pump cord or belt on line *w w*, Fig. 6. Fig. 6 is an enlarged sectional elevation of the same on line *v v*, Fig. 5. Fig. 7 is a cross-section of the same on line *u u*, Fig. 6.

Similar letters of reference indicate corresponding parts.

In the drawings, A represents a shaft, having a bearing in a journal-box, B, that is suspended in a hanger, C; and D represents a drip-pan, suspended by chains *a a* from the box B, and having a well, *b*, formed in one end.

In the eye of a suitable hanger, E, that depends from the beam C', to which the hanger C is fastened, the pump-barrel F is fixed in a vertical position, with its lower end in the well *b* of the drip-pan D, and its bent delivery pipe or spout F', which is provided with a cock, *c*, extended over the oil-opening *d* in the journal-box B. Said pump-barrel F is closed at the bottom with the exception of lateral openings *f f*, through which oil is admitted, and has secured about its lower end over these openings *f f* a filter, G, of wire-gauze or other suitable material, to prevent the ingress of any dirt that may be in the oil.

In the bottom of the pump-barrel F is a bearing or step, *g*, for the end of the pump shaft or rod H.

Above the delivery pipe or spout F', on the opposite side of the pump-barrel F, an opening, *g'*, is made, whereby any excess of oil that may be raised by the shaft or rod H may escape

to flow back into the drip-pan D; and in the upper end of the pump-barrel F, above the eye of the hanger E, is an opening, *g''*, for the escape and return to the pan D of any oil in excess of that required for lubricating the upper part of the rod H, which may be brought up to that point by said rod H. This shaft or rod H has a right-hand screw, *h*, on its lower end for elevating the oil from the drip-pan D, and in its shoulder or bearing H' is formed a right-hand screw-thread, *h'*, that extends upward to about the center of the opening *g''* when said rod H is in position; and a left-hand screw-thread, *h''*, is cut in said bearing H', extending from the top of said rod H down to the upper terminus of the screw-thread *h'*, whereby oil that is raised by the screw-thread *h'* for lubricating the bearing H' is prevented from ascending to the top of the pump, the thread *h''* forcing it out of the opening *g''*, so that it may run down the pump into the pan D.

On the top of the rod or shaft H is a sheave, H², by means of which said rod H is revolved.

In the eye of the hanger E is a horizontal slot, *i*, in which are secured two horizontal arms, I, that are pivoted one above the other, so as to move in a horizontal plane on the pump-barrel F, that passes down through their eyes *i'*. The outer ends of these arms I are vertically slotted, as shown at *i''*. These arms I are designed for the support of the devices K that support and guide the driving belt or cord P of the pump-barrel F.

A belt supporting and guiding device, K, consists of a tube, K', having a parallel oil-reservoir, K², rigidly attached to a side of it and extending the whole length thereof, both tube K' and reservoir K² being closed at the bottom and open at the top. At their upper ends the tube K' and oil-reservoir K² communicate with each other through an opening, *k*, and at their lower ends through an opening, *k'*. These supporting devices K are provided with arms K³, rigidly secured upon them at right angles thereto, near their tops, by means of which arms K³ they are secured to the arms I. Screw-hooks L being passed up through the slots *i''* of the arms I grasp the arms K³, and nuts L' turned on said hooks L hold the devices K immovable.

Entered into the tubes K' and having their

lower ends journaled in the steps *m* in the bottom of said tubes, *K'*, are the rods or shafts *M*, on whose tops, that reach above the said tubes *K'*, are rigidly fixed the guiding-sheaves *N*. The lower ends of these rods or shafts *M* have left-hand screw-threads *n* formed in them, and their upper ends have right-hand screw-threads, *n'*; hence as the said rods *M* are revolved to the left hand oil will be drawn continuously from the reservoir *K²*, through the opening *k'*, up through the tube *K'*, and be forced out of the opening *k* back again into the said reservoir *K²*; hence the rod *M* will be thoroughly lubricated and no oil will escape from the top of the device *K*. In the reservoir *K²* cotton-waste or other filtering substance, as shown at *p*, is placed for filtering the oil from impurities or foreign substances before it enters the tube *K'*. These belt supporting and guiding devices *K* are designed to be secured in the arms *I* at about the angles as shown in Figs. 1 and 2, so that a sufficient quantity of oil can always be retained in the reservoirs *K²* for the lubrication of the rods or shafts *M*.

The oiler is operated by passing an endless cord or belt, *P*, around the shaft *A*, and thence over the sheaves *N N*, that are held a suitable distance apart by a bent rod or stretcher, *O*, which extends between the arms *K³* and is then crossed around the sheave *H²*, the said parts moving in the directions of the arrows, Figs. 1 and 2. Oil from the drip-pan *D* is pumped up by the revolution of the pump-rod *H* and delivered through the spout *F'* into the journal-box oil-opening *d*, the turning of the cock *c* regulating the flow thereof. All the oil running out of the journal-box *B* flows back into the drip-pan *D*, and all excess of oil raised by the pump is expelled through its openings *g'* *g²*, and also flows back to the tank *D* for further use; hence no oil is wasted.

In the belt supporting and guiding devices *K* the operation is analogous, the oil making a continuous circuit of the tubes and reservoirs

K' K², so that the lubrication of the rods *M* is automatic.

With this oiler applied to lines of shafting and machinery of various kinds great economy in oil can be effected, and all dust and other foreign substances be prevented from getting into the journal-boxes.

I do not confine myself to the precise mechanism as herein shown and described, as it is evident that it may be modified without departing from my invention.

Having thus described my invention, I claim as new and desire to secure by Letters Patent—

1. In the construction of a machine-oiler, a pump consisting of barrel *F*, provided with spout *F'*, having regulating-cock *c*, having lateral overflow-openings *g' g²*, and screw-rod *H*, having bottom screw-threads for raising the oil and top screw-threads for forcing the oil down, and provided with sheave *H²*, substantially as herein shown and described.

2. In a machine-oiler, the combination, with the hanger *E* and pump *F H*, of the pivoted slotted arms *I I* and screw-hooks and nuts *L L'*, substantially as herein shown and described, whereby the belt supports and guides are adjustably held, as set forth.

3. In a machine-oiler, the combination, with the pump *F H* and adjustable-supporting arms *I*, of the belt supporting and guiding devices *K*, consisting of tubes *K'*, attached oil-reservoirs *K²*, arm *K³*, and screw rod or shaft *M*, carrying sheaves *N*, substantially as herein shown and described.

4. The combination, with the drip-pan *D* and shaft *A*, of the screw-pump *F H*, provided with filter *G*, adjustable arms *I*, belt supporting and guiding devices *K*, and belt *P*, substantially as herein shown, and for the purpose described.

JOHN SCOTT WHITNEY.
